DESIGN FOR A DISPENSING CAP

Joseph E. Gaudreau, South Ashburnham, Mass.

Application November 22, 1939, Serial No. 88,428

Term of patent 7 years

To all whom it may concern:

Be it known that I, Joseph E. Gaudreau, a citizen of the United States, residing at South Ashburnham, in the county of Worcester and State of Massachusetts, have invented a new, original, and ornamental Design for a Dispensing Cap, of which the following is a specification, reference being had to the accompanying drawing, forming part thereof.

I claim:

The ornamental design for a dispensing cap, as shown.

JOSEPH E. GAUDREAU.
